UNITED STATES PATENT OFFICE.

JOHN E. WADE, OF NEW YORK, N. Y.

CAR-COUPLING.

SPECIFICATION forming part of Letters Patent No. 764,323, dated July 5, 1904.

Application filed January 2, 1904. Serial No. 187,472. (No model.)

To all whom it may concern:

Be it known that I, JOHN E. WADE, a citizen of the United States, residing at the borough of Brooklyn, city of New York, county of Kings, and State of New York, have invented 5 certain new and useful Improvements in Car-Couplings, of which the following is a specification, reference being had therein to the accompanying drawings, which form a part 10 thereof.

My invention relates to car-couplings, and more particularly to a class thereof especially adapted for use in the street-railway or other similar service wherein the draw-bar and the 15 draft-rigging are carried by the underframe of the car.

The main object of the invention is to provide a car-coupling the head of which will be so constructed as by contact with an opposed 20 coupling to force it into such alinement therewith when coupling on a curve as will insure an automatic locking of the couplings.

A further object is to provide a coupling which through a conjoint action of the car- 25 body and a swivel-truck will so swing the coupling when taking a curve as to always bring it in substantially the center of the track, so as to insure the automatic locking thereof with a similar opposed coupling; and 30 a still further object is to provide a coupling which will have a simple construction and arrangement as to both the draft-rigging and coupler-head, be light and strong, and which may be adapted for use in connection with the 35 various types of cars now ordinarily employed in the street-railway and similar services.

The invention consists, primarily, in providing in a car-coupling a draw-bar pivotally mounted on the underframe of the car adjacent to the end thereof and a draw-head having a movable locking-jaw, a buffer-face disposed in front of said jaw and adapted to contact with the side horn of an opposed coupling, a horn opposite to said jaw projected laterally of the head whereby contact of said 45 horn with the buffer-face of an opposed coupling will be at a point well within the chord of an arc, including the pivotal point of both draw-bars, and in such other novel features 50 of construction and arrangement of parts as

are hereinafter set forth and described, and more particularly pointed out in the claims hereto appended.

Referring to the drawings, Figure 1 is a plan view of adjacent swivel-trucks of two cars on a curve, showing the relative position of the 55 couplings and draft-rigging to each other, the trucks and the car-body, the respective trucks being provided with different adaptations of my invention and the car-bodies being indicated in dotted lines. Fig. 2 is a plan view showing one form of the draft-rigging and the relative position of the draw-heads on 60 opposed couplings when meeting on a curve. Fig. 3 is a plan view of another form of draft-rigging by which the invention is adapted to 65 cars wherein the point of pivotal connection of the draw-bar is well in advance of the truck. Fig. 4 is a view on the line 4 4 of Fig. 2. Fig. 5 is a view on the line 5 5 of Fig. 2, and Fig. 6 70 is a plan view of the draw-head with the locking-jaw entirely removed.

Like letters refer to like parts throughout the several views.

In the drawings, A indicates the bolster of 75 the truck, which is provided with the usual king-bolt connection B with the underframe of the car.

C indicates the car-body, and D the rails on 80 a curve, which for purposes of illustration is of a radius approximating ninety degrees, a curve much sharper than is ordinarily found on street or other railways.

In the street-railway, elevated railways, and other similar railways the swivel-trucks are 85 usually set well forward of the car-body, and a coupling employing a short draw-bar is employed, said draw-bar usually being mounted on some part of the underframe of the car-body, either adjacent to the king-bolt, as 90 shown at the left, Fig. 1, or adjacent to the end of the car-body, as shown at the right of said figure. In the double or swivel truck cars the action of the car-body on a curve is such as to project the coupling-head on a line, 95 which prevents contact of opposed couplings and the interlocking of the same automatically. To avoid these difficulties, I provide a coupling having a draw-head a, provided with a locking-jaw b, which owing to the semiro- 100

tary movement of the heads in coupling on a curve preferably slides laterally in a way c , formed in said draw-head. To prevent the escape of the said jaw b , the head a is provided with an abutment c' and the way c with an inclined portion c^2 and an offset horizontal shoulder or set c^3 , extending from a point adjacent to the lower portion of the part c^2 , which parts coöperate with a corresponding guide-surface b' , a vertical shoulder b^3 , and a horizontal abutment b^2 on the jaw b . To prevent a direct vertical movement of said jaw b , I preferably provide it with an inclined guide b^4 , extending parallel with the guide-surface b' , which moves in a way d in said draw-head, having a bearing-face disposed oppositely to that of the said surface b' . The pitch of the ways b' and d is such as permits the complete withdrawal of the jaw b within the head when coupling and insures its return by gravity to the locking position, so as to have the coupling normally in that position. To facilitate the release of interlocked couplings, each said jaw b is provided with means whereby it may be manually drawn within its draw-head, as the hook b^5 . In front of this head a I provide a buffer-facing comprising an abutment a' , presenting outwardly converging bearing-faces and a contact a^2 , adapted, respectively, to enter the jaws of an opposed coupling and in conjunction with the side horn thereof prevent a lateral separation of the couplings and to force said couplings into the operative position in case the same are not exactly in proper alinement, as will hereinafter appear, and to engage the said horn of an opposed coupling and cause said coupling to swing about said contact as a fulcrum into the locked position. The part of the head about the jaw b and its buffer-faces is enlarged to an extent to give the required strength of material to resist heavy impacts, and the head is gradually tapered back into the draw-bar e to avoid unnecessary weight.

To insure the proper engagement of opposed couplings on a curve, I provide a side horn f to the head a , which projects laterally of the head to a point which will bring it well within the chord of an arc including both points of pivotal connection of the draw-bars of opposed couplings, as described. The horn f , being designed for use more particularly in coupling on a curve where the draw-heads contact on an angle, is set back of the locking-jaw, its lateral projection occasioning the proper impact and operation of said couplings. The space in each head a between the horn f and the locking-jaw b is shaped to conform to the contour of the abutment a' and the beveled forward face of said locking-jaw.

While the dimensions of the heretofore-described parts are not material except relatively to each other, I preferably make the draw-head about six inches deep, the draw-bar about one and one-half by four and one-

half inches, and the head about eighteen inches wide, including the laterally-projected side horn f . On very short couplings, such as would ordinarily be used on single-truck cars, the width of the head should approximate that of the entire length of draw-bar forward of the pivot.

In double or swivel truck cars the draw-bar e is pivotally connected to the car-body at a point forward of the king-bolt B by means of a pivot g , and, if desired, any well-known form of spring-draft rigging g' , as shown in Fig. 2, may be used. This point of connection being in front of the king-bolt and not concentric therewith the movement of the car-body on a curve will tend to project the draw-head beyond the line of the curve, as above described, and to prevent this and draw it well within the curve, so that the horns f thereof will be within the chord of the arc, as above specified, I provide a pivotal connection, as the link h , between the draw-bar e at a point forward of its connection with the car-body and with the bolster-frame, Fig. 2, or an extension thereof, as i , Fig. 3, the pivots of which are parallel with that of the draw-bar and each other, so as to cause it to describe an arc which will bring it as desired. This construction is desirable, inasmuch as the draw-head moves in an arc of a shorter radius than that of the truck, and the point of pivotal connection of the two being adjacent to the pivot of the former a direct connection would compound this movement of the draw-head to an extent which would prevent one of the objects of the invention. By the use of an interposed link or pivotal connection h the swiveling of the truck in either direction will always occasion a proportionate movement of the draw-head in that direction and when on a straight track will properly center the said head, so that it will be free to turn in either direction as described. To admit of the slight movement of the head in coupling, it is essential that the link h or its support be so constructed as to allow a certain amount of give under pressure, as by the slot and spring k , Fig. 2, or the spring-support l between the extension i and the bolster.

The operation of the heretofore-described coupling is substantially as follows: On a straight track the coupling-heads a will always be substantially alined and will therefore contact head on, the beveled faces of the jaws b or either of them forcing the other within the head to an extent to permit the passage of the other within the jaws. This movement being on the inclined portion c^2 of the way c gravity causes either jaw to assume the locked position instantly upon its release by the other. The guide b^4 prevents a direct vertical movement of the jaw b either through the force of impact of the opposed coupling or the jolting of the car-body while in motion. On a curve, however, the heads a , al-

though always substantially alined, approach each other at a slight angle, and the initial impact is between the laterally-projected horn f of one coupling and the contact a^2 of the other, as shown in Fig. 2. If the relation of the heads is such as not to insure such contact, the converging faces of the abutment a' will force the horn into the desired position either by contact with the horn or with the abutment of the opposed coupling. On account of the lateral projection of the horn f this point of impact will be well within the chord of an arc, including both the pivots g , so that the direct pressure of one coupling 15 against the other will cause the couplings to swing toward the center of said arc, the point of contact between said horn f and contact a^2 acting as a fulcrum to occasion a sort of rolling motion of both heads a , forcing the 20 jaws b , one behind the other, within the respective jaws and automatically locking them. The abutment a' once within the jaws prevents any lateral movement of the head and a reversal of this action. A spring-draft rigging will minimize the effects of the impact 25 in the usual manner.

The pivotal connection or link h when on a straight track is alined with the draw-bar e ; but on a curve the swiveling of the truck A 30 turns it about the point of its pivotal connection with the draw-bar and simultaneously draws the said bar e in the direction of the curve, the extent of which movement, owing to the arrangement of the connecting parts 35 being gradual and such as to project the draw-head a at such an angle to both the bolster A and car-body C as to always bring it into substantially the coupling position on any curve. The support k or l permits sufficient independent movement of the link to permit the slight rotation of the draw-head in coupling, as described, and also that direct longitudinal movement due to the spring-draft rigging when such is used. The length of the link 40 45 h must be determined by the distance between the king-bolt B and the point of its pivotal connection with the bolster, an increase in such distance necessitating a link of greater length to insure the proper lag of the draw-bar relative to the swivel of the truck, and 50 compensate for the double center and complex actions of the truck and draw-bar pivots.

It is not my intention to limit the invention to the precise construction herein shown and 55 described, as it is apparent that there must be a considerable latitude as to such to accommodate the coupling to various models of car-trucks and car-bodies.

Having described the invention, what I 60 claim, and desire to have protected by Letters Patent, is—

1. In a car-coupling, a draw-bar, means whereby said bar is pivotally mounted on the car-body, a draw-head, a locking-jaw mounted 65 therein, a buffer-face in front of said locking-

jaw comprising outwardly-converging bearing-faces and a contact and a side horn to the rear of said buffer-face and locking-jaw, projected laterally of said draw-head and adapted to contact with the buffer-face of an opposed coupling to swing both into the locked position, when coupling on a curve.

2. In a car-coupling, a draw-bar, means whereby said bar is pivotally mounted on the car-body, a draw-head, a laterally-sliding locking-jaw mounted therein, a buffer-face in front of said locking-jaw comprising outwardly-converging bearing-faces and a contact and a side horn to the rear of said buffer-face and locking-jaw, projected laterally of said draw-head and adapted to contact with the buffer-face of an opposed coupling to swing both into the locked position, when coupling on a curve.

3. In a car-coupling, a draw-bar, means whereby said bar is pivotally mounted on the car-body, a draw-head having an inclined way therein, a locking-jaw mounted in said way, abutting shoulders in said way and on said jaw whereby said jaw is maintained within said way, a buffer-face in front of said locking-jaw and a side horn to the rear of said buffer-face and locking-jaw, projected laterally of said draw-head and adapted to contact with the buffer-face of an opposed coupling to swing both into the locked position, when coupling on a curve.

4. In a car-coupling, a draw-bar, means whereby said bar is pivotally mounted on the car-body, a draw-head, parallel inclined ways therein, a locking-jaw mounted in one of said ways, abutting shoulders in said way and on said jaw whereby said jaw is maintained within said way, an inclined guide carried by said jaw and moving in said other way, a buffer-face in front of said locking-jaw and a side horn to the rear of said buffer-face and locking-jaw, projected laterally of said draw-head and adapted to contact with the buffer-face of an opposed coupling to swing both into the locked position, when coupling on a curve.

5. In a car-coupling, a draw-bar, means whereby said bar is pivotally mounted on the car-body, a draw-head, a locking-jaw mounted therein, a buffer-face comprising outwardly-converging bearing-faces and a contact on the outside thereof, in front of said locking-jaw and a side horn to the rear of said buffer-face and locking-jaw, projected laterally of said draw-head and adapted to contact with the buffer-face of an opposed coupling to swing both into the locked position, when coupling on a curve.

6. In a car-coupling, a draw-bar, means whereby said bar is pivotally mounted on the car-body, a draw-head, a locking-jaw and a side horn thereon, and a pivotal connection between said draw-bar and a swivel-truck comprising a link the pivot of one end of which is movable with the truck, and the other pivot-

point of which moves with said draw-bar, the said pivots being parallel with that of the draw-bar and each other whereby said draw-bar will be held centrally of the car-body on a straight track and swung laterally thereof on curves, in the general direction of the curve.

7. In a car-coupling, a draw-bar, means whereby said bar is pivotally mounted on the car-body, a draw-head, a locking-jaw and a side horn thereon, and a pivotal connection between said draw-bar and a swivel-truck comprising a link, the pivot of one end of which is movable with the truck, and the other pivot-point of which moves with said draw-bar, the said pivots being parallel with that of the draw-bar and each other whereby said draw-bar will be held centrally of the car-body on a straight track and swung laterally thereof on curves, in the general direction of the curve, and means whereby said link is permitted to give during the coupling with an opposed coupling.

8. In a car-coupling, a draw-bar, means whereby said bar is pivotally mounted on the car-body, a draw-head, a locking-jaw mounted therein, a buffer-face in front of said locking-jaw, a side horn to the rear of said buffer-face and locking-jaw, projected laterally of said draw-head and adapted to contact with the buffer-face of an opposed coupling to swing both into the locked position when coupling on a curve, and a pivotal connection between said draw-bar and a swivel-truck comprising a link, the pivot of one end of which is movable

with the truck, and the other pivot-point of which moves with said draw-bar, the said pivots being parallel with that of the draw-bar and each other whereby said draw-bar will be held centrally of the car-body on a straight track and swung laterally thereof on curves, in the general direction of the curve.

9. In a car-coupling, a draw-bar, means whereby said bar is pivotally mounted on the car-body, a draw-head, a laterally-sliding locking-jaw mounted therein, a buffer-face in front of said locking-jaw, a side horn to the rear of said buffer-face and locking-jaw, projected laterally of said draw-head and adapted to contact with the buffer-face of an opposed coupling to swing both into the locked position when coupling on a curve and a pivotal connection between said draw-bar and a swivel-truck comprising a link, the pivot of one end of which is movable with the truck, and the other pivot-point of which moves with said draw-bar, said pivots being parallel with that of the draw-bar and each other whereby said draw-bar will be held centrally of the car-body on a straight track and swung laterally thereof on curves, in the general direction of the curve.

In witness whereof I have hereunto affixed my signature, this 28th day of December, 1903, in the presence of two witnesses.

JOHN E. WADE.
